(57) **CLAIM**

The ornamental design for a truck vehicle, as shown and described.

DESCRIPTION

FIG. 1 is a front perspective view of the truck vehicle of the present invention as the same could be mounted within a vehicle;

FIG. 2 is a top plan view of the truck vehicle of the present invention;

FIG. 3 is a front elevation view of the truck vehicle of the present invention, which is substantially similar to its rear elevation view;

FIG. 4 is a side elevation view of the front truck vehicle of the present invention; and,

FIG. 5 is a bottom plan view of the truck vehicle of the present invention.

The broken line drawings in FIG. 1 are for illustrative purposes only and form no part of the claimed design.
